[57] CLAIM

The ornamental design for a portable light support or similar article, as shown and described.

DESCRIPTION

FIG. 1 is a perspective view of a portable light support or similar article showing my new design;

FIG. 2 is a top plan view thereof;

FIG. 3 is a bottom plan view thereof;

FIG. 4 is a side elevational view thereof;

FIG. 5 is a front elevational view thereof;

FIG. 6 is a perspective view of one of the two identical sections which make up the claimed design, the second section being omitted in this view and the following views for purposes of disclosure;

FIG. 7 is a front elevational view thereof;

FIG. 8 is an interior view thereof;

FIG. 9 is a rear elevational view thereof;

FIG. 10 is an exterior view thereof;

FIGS. 11 and 12 are respectively top and bottom plan views thereof.
